GLAZIER'S POINT

Charles W. Skinner and Edward Raymond Morris,
Brockton, Mass., assignors to themselves, doing
business as Standard Devices Company, a
copartnership

Application October 28, 1938, Serial No. 237,384

4 Claims. (Cl. 85—15)

This invention relates to points such as are used by glaziers for securing window panes in position preparatory to puttying.

One object of the invention is to provide a point which can be set with great ease and without other tools than a putty knife, screwdriver, or the like, and that may be made very cheaply and with a small amount of metal and substantially without waste.

10 The point comprises, therefore, essentially a tack having a flat shank and point, and a head having a part in alinement with the shank and a part turned outwardly therefrom and forming with the other part an angular abutment within 15 which may be engaged the end of a tool such as a putty knife, screwdriver, or the like, so that by exerting pressure on the tool the point may be forced into the sash and tight against the pane being set.

20 For a more complete understanding of this invention, reference may be had to the accompanying drawing in which—

Figure 1 is a perspective view of a flat shank tack from which the point of this invention may 25 be made.

Figure 2 is a section on line 2—2 of Figure 1.

Figure 3 is a perspective view of the point made from the tack of Figure 1.

Figure 4 is a section on line 4—4 of Figure 3.

30 Figure 5 is a view similar to Figure 4, but showing a modified construction.

Figure 6 is a perspective view illustrating the manner in which blanks to be formed into the points of this invention may be cut from sheet 35 stock.

Figures 7 and 8 are somewhat diagrammatic sectional views illustrating successive steps in the formation of a point from the blank shown in Figure 6.

40 Figure 9 is a perspective view of the point formed by the method illustrated in Figures 7 and 8.

Figure 10 is a fragmentary section through a window sash showing the point of Figure 3 in 45 driven position.

Referring first to Figures 1 and 2 of the drawing, there is indicated a tack having a flat shank 1 terminating in a point 2 and having a flat head 3. Such a tack may be formed up in the usual 50 manner on a tack machine, the shank portion, however, being formed up between dies which produce the flat thin shank having its width substantially greater than its thickness as shown. Such a tack may then be formed into the point 55 of this invention by bending substantially one-

half of the head 3 at one side of the flat shank 1 into substantial alinement with the shank as shown at 4 in Figures 3 and 4. This produces a point having the flat pointed shank 2 sharpened both in width and thickness which may be driven 5 into the sash 5, as shown in Figure 10, the imperforate portion 4 of the point overlying the glass or window pane 10, and the portion 11 of the point head, which remains in its original position, forming an abutment engaging the sash and holding the shank in its proper position penetrating straight into the sash. The portion 11, therefore, acts as an abutment which holds the point against lateral tilting, and it also provides a head which may be engaged by the end of the putty 10 knife, screwdriver, or other similar tool by which pressure may be exerted to force the point into its proper place. The portion 4 of the head also acts as an abutment to hold the tool in proper position during the driving operation. As the 20 shank portion itself is relatively narrow, it is desirable that the head be substantially wider than the shank in order to form a broad bearing for the tool by which the point is forced into position, and to form an engagement of sufficient 25 length on the sash to insure against tilting of the point when driven. The ordinary formation of the flat shank tack in a tack machine will of itself produce a head of the desired width greater than that of the shank.

30 The point may, however, be formed by other means. For example, in Figure 5 the point is illustrated as formed by casting. This may be done using an alloy similar to type metal such as commonly used in Linotype and Monotype machines, 35 but preferably provided with a somewhat larger proportion of the stiffer metal constituent of the alloy, such as tin, in order to increase the strength of the point. The casting, however, may be performed in a manner quite similar to 40 that commonly employed in type casting.

Another method of forming up the point on a 45 tack machine is illustrated in Figures 6 to 8. Referring to Figure 6, the individual blanks from which the points are made may be cut from a strip of sheet metal of suitable gage as shown at 30. In accordance with the usual practice in tack making operations, this strip is cut diagonally and alternately in oppositely inclined directions to form the longitudinally tapered blanks 50 31. Each blank is then subjected to forming operations between dies 32 and 33 (see Figures 7 and 8) which form the narrower end portion of each blank into the desired flat tapered shank shown at 34 in Figures 7, 8 and 9. Preferably 55

the dies forming this shank portion are offset from the wider end portion of the blank. A die 35 forms an abutment for one side of the upper portion of the blank, and then a cutting die 36 is moved from the position of Figure 7 to that of Figure 8, shearing off a portion lengthwise from the wider portion of the blank and forming it into a flange 38 corresponding generally in shape and size to the head portion 11 of the point formed 10 up from the tack as shown in Figures 1 to 4. The remaining portion of the larger end of the blank is then left as an imperforate projection 40 lying in alignment with the flat shank 34 and extending beyond the flange 38 on the side opposite to the shank 34. The driving of the point formed in this manner is the same as that for driving the points constructed in the manner shown in Figures 1 to 4, or cast as in Figure 5.

The points made in accordance with this invention are easy to set, and due to the small size necessary for the shank portions, may be made from metal in amount of about one-half of that required for the usual triangular points, so that there is marked economy in the amount of metal required when constructing the points in accordance with this invention.

From the foregoing description of certain embodiments of this invention, it should be evident to those skilled in the art that various other changes and modifications might be made without departing from the spirit or scope of this invention as defined by the appended claims.

We claim:

1. A glazier's point having a thin pointed shank adapted to be forced into a sash outwardly of the glass and an integral head on said shank having a portion lying substantially in alignment with said shank and adapted to overlie the glass and a single thickness portion extending laterally thereof on one side only and adjacent to the juncture of said shank and portion and extending the full width of said shank and adapted to extend outwardly from the glass and

to form an abutment limiting the depth to which the point may be driven into the sash.

2. A glazier's point having a thin pointed shank adapted to be forced into a sash outwardly of the glass and an integral head on said shank having a portion lying substantially in alignment with said shank and adapted to overlie the glass and a single thickness portion extending laterally thereof on one side only and adjacent to the juncture of said shank and portion and adapted to extend outwardly from the glass and to form an abutment limiting the depth to which the point may be driven into the sash, said lateral extending portion extending across the full width of said shank and being of a width substantially greater than that of said shank.

3. A glazier's point having a thin pointed shank tapered in both width and thickness adapted to be forced into a sash outwardly of the glass, and an integral head on said shank having a portion lying substantially in alignment with said shank and adapted to overlie the glass and a single thickness portion extending laterally thereof on one side only adjacent to the juncture of said shank and portion and extending the full width of said shank and adapted to extend outwardly from the glass and to form an abutment limiting the depth to which the point may be driven into the sash.

4. A glazier's point having a thin pointed shank adapted to be forced into a sash outwardly of the glass and an integral imperforate head on said shank having a portion lying substantially in alignment with said shank and adapted to overlie the glass and a single thickness portion extending outwardly from the glass adjacent to the juncture of said shank and portion and along the outer face of said shank to form an abutment limiting the depth to which the point may be driven into the sash.

CHARLES W. SKINNER,
EDWARD RAYMOND MORRIS.
